RETARDED-RELEASE VALVE.

1,039,219.

Specification of Letters Patent. Patented Sept. 24, 1912.

Application filed January 13, 1905. Serial No. 240,902.

To all whom it may concern:

Be it known that I, WALTER V. TURNER, a citizen of the United States, residing in Wilkinsburg, in the county of Allegheny and State of Pennsylvania, have invented 5 a certain new and useful Improvement in Retarded-Release Valves, of which the following is a specification.

This invention relates to automatic air 10 brake systems, the principal object being to provide an improved valve device operating upon an increase in train pipe pressure for releasing brakes, to retard the release of the brakes on the forward end of the train 15 by temporarily closing or restricting the brake cylinder exhaust port, whereby as the wave of increase in train pipe pressure travels through the train pipe and actuates the triple valves at the rear end of the 20 train, a substantially simultaneous release of all the brakes will be effected.

With the present standard automatic air 25 brake apparatus, as is well known, the release movement of the triple valve is produced by an increase in train pipe pressure which accumulates rapidly at the head end of the train pipe, but requires some little time to travel to and actuate the triple 30 valves at the rear end, especially on long trains, the result of this being that when a release is made before coming to a full stop, the head brakes are often released considerably in advance of the rear brakes thereby 35 permitting a surging ahead of the forward end of the train, while the brakes on the rear cars are still applied, which action is productive of violent shocks and strains and often causes a break-in-two of the train.

In my prior application, Ser. No. 198,762, 40 filed March 18, 1904, I have disclosed a triple valve having a retarding spring for opposing the movement of the valve from full release position, in which the brake cylinder exhaust port is fully open, to a 45 retarded release position in which the exhaust port is restricted, and for normally returning the valve from the retarded position to full release position when the pressures substantially equalize upon opposite 50 sides of the triple valve piston. This device is found to operate very satisfactorily in practice, but it is of course necessary to provide a spring of sufficient power to

overcome the friction of the slide valve in order to return the same to full release position. On very long trains it is sometimes difficult, owing to the length of the train pipe, to produce a sufficiently rapid increase in the pressure toward the rear end of the train, at the time of releasing the brakes, 60 to cause the piston to compress the spring and move the valve far enough to restrict the exhaust port. 55

According to my present improvement, a smaller valve is used for controlling the exhaust and this is preferably in the form of a graduating slide valve operated by the triple valve piston and mounted upon the main slide valve and having a limited relative movement for controlling exhaust ports 70 in the main slide valve. By means of this construction a much lighter spring may also be employed, since it need be only of sufficient power to overcome the friction of the smaller valve, so that the action of the device will be rendered more sensitive and effect a proportionate retard of the release 75 even toward the rear end of long trains.

Another important feature of my present invention comprises means, operating at the 80 time of releasing brakes, for momentarily reducing the pressure upon one side of the piston or other movable abutment operating the retarded release valve, whereby the valve will be immediately carried to its extreme position for retarding the release and then assume its proper position according to 85 the rate of rise in train pipe pressure corresponding to the relative location of the valve in the train from the head to the rear. 90

While these features of my invention may be used in connection with any valve device for controlling the brake cylinder exhaust, they are preferably applied to the triple valve device, and this is arranged to momentarily open communication from the triple valve chamber to the atmosphere or other space for the purpose of producing a momentary reduction on the auxiliary reservoir side of the triple valve piston at 100 the time that the same moves from service or lap position toward release position. The train pipe pressure then instantly moves the piston and valve to the extreme retarded release position in which the spring 105 is compressed and communication is open

for the feeding of air under pressure from the train pipe around the piston.

According to another feature of my invention, the valve device is provided with means for closing or restricting the communication from the auxiliary reservoir to the valve chamber in the retarded release position and for opening this communication as the valve returns to its normal full release position under the action of the spring as the pressure equalizes upon the piston.

In the accompanying drawing: Figure 1 is a sectional view showing my invention applied to a triple valve device, the section being taken on the line $x-y$ of Fig. 6, with the valve in normal full release position; Fig. 2 a similar sectional view, taken on the line $y-y$ of Fig. 6, and showing the valve in service application position; Fig. 3 a similar sectional view, taken substantially on the line $x-z$ of Fig. 6, and showing the valve in position for venting the valve chamber to the atmosphere while moving to the retarded release position; Fig. 4 a similar sectional view, on the line $x-y$ of Fig. 6, showing the parts in retarded release position; Fig. 5 a plan view of the main slide valve seat; Fig. 6 a face view of the main slide valve; Fig. 7 a face view of the small graduating slide valve; and Fig. 8, a similar view with the small extension cavity omitted.

According to the construction shown, the casing is provided with the usual piston chamber 1 and valve chamber 2, containing the movable abutment or piston 3, stem 4, main slide valve 5, and small graduating slide valve 6, the casing having the usual connection 7 to the train pipe which communicates with the piston chamber 1. The end of the valve chamber is closed by a cap 11, in which is located a resistance spring 9 and stop 10 for engaging the end of the piston stem 4 when the piston moves from its normal release position farther inward to a position for closing or restricting the exhaust port and retarding the release. In the main slide valve seat the port 12 communicates with the auxiliary reservoir 13, and port 14 with passage 15 leading to the brake cylinder, while exhaust ports 16 and 17 lead to the atmosphere. The main slide valve is provided with service port 18, ports 19 and 20 for the brake cylinder exhaust, port 21 for connecting with auxiliary reservoir port 12, and port 22 for venting air from the valve chamber in a certain position of the valve. In the small auxiliary or graduating valve 6 is formed a cavity 23 which may have a small extension 24, and this valve is preferably mounted to move with the piston stem upon the main slide valve and has a certain independent movement relative thereto. A fixed stop 26

limits the inward travel of the main slide valve and defines its release position in which the ports 19 and 20 register respectively with the brake cylinder port 14 and exhaust port 16.

When the system is charged up to the normal standard pressure the parts of the valve device stand in the normal release position, as indicated in Fig. 1, in which communication is open from the train pipe around the piston 3 through the feed groove 8 to the valve chamber 2 and to the auxiliary reservoir through ports 21 and 12. At the same time the brake cylinder is open to the atmosphere through ports 14, 19, cavity 23 and ports 20 and 16. When a service application of the brakes is made by reducing the train pipe pressure in the usual way, the piston with the small graduating valve first moves outward until the head of the piston stem engages the main slide valve, during which movement the graduating valve uncovers the service port 18 and closes the exhaust ports 19 and 20 and the vent port 22 in the main slide valve. The piston continues its outward movement carrying along the main slide valve to service position, in which it engages the usual graduating stem, as indicated in Fig. 2. During this movement of the main slide valve, the large port 12 is uncovered and the vent port 22 passes over the exhaust port 17, but no air can escape, as the graduating valve 6 covers the port 22. In service position, the service port 18 registers with the brake cylinder port 14, and air under pressure from the auxiliary reservoir flows to the brake cylinder, charging the same in the usual way. As the auxiliary reservoir pressure falls to or slightly below that of the train pipe the piston moves the graduating valve to lap position in the ordinary manner, closing the service port 18 and the port 21, uncovering vent port 22, and connecting ports 19 and 20 through the cavity 23 and the restricted extension 24. When the train pipe pressure is increased for releasing the brakes, the piston starts to move the parts inward in this relative position, the first part of the movement serving to close the auxiliary reservoir port 12 and to register the vent port 22 with exhaust port 17, as indicated in Fig. 3. In this position the piston stem engages the yielding stop 10, and as the air in the valve chamber vents to the atmosphere through ports 22 and 17 a very decided reduction in pressure is produced upon the auxiliary reservoir side of the piston, whereupon the train pipe pressure acts to immediately force the piston to the extreme inward retarded release position, as shown in Fig. 4, compressing the resistance spring 9 of the yielding stop 10 until the main slide valve strikes the fixed stop 26. In this position the brake cylinder

exhaust is closed when the small extension cavity of the graduating slide valve is omitted, as shown in Fig. 8, or restricted to the extent of the small extension cavity 24 in the graduating slide valve as shown in Fig. 7, and the feed groove 8 opens communication from the train pipe to the valve chamber. The pressure then begins to equalize around the piston and the graduating valve will be held in a position in which the exhaust is closed or more or less restricted for a short period of time, depending upon the rate of increase in the train pipe pressure corresponding to the position of the triple valve in the train from the front to the rear end. When the engineer's brake valve is thrown to release position for supplying air from the main reservoir to the train pipe in releasing brakes, the pressure builds up very rapidly at the head end of the train line, but as the wave of increased pressure flows toward the rear, it is retarded by frictional resistance along the pipe until at the rear end of long trains the rate of increase is greatly diminished and an appreciable period of time is required to effect the release movement of the rear triple valves. During this interval the exhaust upon the forward cars is held closed or more or less restricted by the more rapid rate of increase in train pipe pressure in order to prevent the earlier complete release of those brakes and to secure a substantially simultaneous release throughout the train.

When the feature of venting air from the auxiliary reservoir side of the piston is employed, it will be noted that each triple valve piston as it moves to release will be carried to its extreme inner retarded release position, but at the rear end of the train the pressure will immediately substantially equalize on opposite sides of the piston owing to the slow rate of increase in train pipe pressure, whereupon the resistance spring operates to return the piston and graduating valve to full release position. By means of this feature it is not necessary to depend entirely upon the rate of increase in train pipe pressure over that of the auxiliary reservoir for effecting the compression of the resistance spring and the movement of the piston to its retarded release position, and the spring may then be of such strength as to readily return the valve to full release position when the desired relation between the pressures upon opposite sides of the piston is attained. It is not necessary to the practical operation of my invention that the valve chamber should be cut off from the auxiliary reservoir when the valve moves to retarded release position, although such is the preferred construction, since the vent port 22 may then be very small, as it is only the pressure in the valve

chamber that is reduced which causes prompt movement of the piston to its inner position. With this construction the graduating valve then covers the port 21, controlling communication with the auxiliary reservoir, so that as the train pipe pressure is increased air flows through the feed groove and raises the pressure in the valve chamber. At the head end of the train the rapid increase in train pipe pressure will hold the piston and valve at its inner position with port 21 closed and the exhaust port closed or restricted until the pressure in the valve chamber has risen with that of the train pipe to near the equalization point, whereupon the spring operates to return the graduating valve toward normal release position. But as soon as the port 21 is opened the flow of air from the valve chamber into the auxiliary reservoir, which is at a lower pressure, checks the movement of the piston and valve and the train pipe pressure acting on the piston will hold the valve at this intermediate position until the auxiliary reservoir pressure rises to nearly that of the train pipe, when the spring acts to return the graduating valve and piston to full release position. The restricted portion of the exhaust cavity may be so formed as to restrict the exhaust port either more or less as desired, at this intermediate position of the valve, and the extent to which the release is retarded upon the forward portion of the train may thereby be adjusted to suit different conditions. At the rear of the train, where the increase in train pipe pressure is slow, the valve will not pause materially at the intermediate position, but will be immediately returned by the spring to its normal full release position, since the pressure in the valve chamber and the auxiliary reservoir will increase at substantially the same rate as the train pipe. At other portions of the train the release will be retarded in proportion to the variation in train pipe pressure from the front to the rear and may be effected substantially at the same time throughout the train, or, if desired, may be made to occur from the rear toward the forward end. Another advantage of controlling the auxiliary reservoir port in the main slide valve with the graduating valve is that in normal release position the auxiliary reservoir is not cut off from the valve chamber and there is no danger of failure to move the triple piston by a reduction in train pipe pressure. In emergency applications the piston operates under a sudden reduction in train pipe pressure to move the main slide valve out to emergency position, in which the graduating spring is compressed and the auxiliary reservoir pressure equalizes into the brake cylinder through the ports 25 and 14 in the usual way.

While I have described in detail one form

of valve device, it is to be understood that my invention is not limited to this construction but may be applied to any valve device controlling a brake cylinder exhaust. It will 5 also be evident that my invention may be employed either with or without the feature of venting air from one side of the movable abutment in operating the valve, and that as applied to a triple valve device the valve 10 chamber may or may not be cut off from the auxiliary reservoir in retarded release position.

Having now described my invention, what I claim as new and desire to secure by Letters Patent is:—

1. A valve device for controlling a brake cylinder exhaust, comprising a main valve having an exhaust port, or ports, a secondary valve having a movement relative 20 to the main valve for controlling said exhaust port, or ports, a movable abutment operated by train pipe pressure to move said secondary valve to restrict said exhaust, and yielding resistance means for opposing the movement of said secondary valve to its restricted position.

2. In a fluid pressure brake, the combination with a main valve having a brake cylinder exhaust port, a secondary valve having a normal full release position in which said port is fully open, and a retarded release position in which said port is restricted, of a movable abutment operated by train pipe pressure for moving said secondary valve to its retarded release position, and yielding resistance means for returning the same to full release position.

3. In a fluid pressure brake, the combination with a valve for controlling the brake cylinder exhaust, and a movable abutment for operating said valve, of means operating at the time of releasing brakes for reducing the pressure upon one side of said abutment to move said valve to restrict the exhaust 45 port, and yielding resistance means for opposing this movement.

4. A retarded release valve device for fluid pressure brakes, comprising a movable abutment and valve for controlling the 50 brake cylinder exhaust, means operating upon an increase in train pipe pressure for causing a sudden variation of pressure upon one side of said abutment to move said valve to restrict the exhaust, and yielding resistance means for returning said valve to full release position.

5. A retarded release valve device comprising a valve for controlling the brake cylinder exhaust and having a normal full 60 release position and a retarded release position, a movable abutment subject to train pipe pressure for operating said valve, means operating upon an increase in train pipe pressure for venting air from one side 65 of said abutment and moving said valve

to retarded release position, and yielding resistance means for returning the valve to full release position.

6. A triple valve device comprising a main valve having a brake cylinder exhaust port, a secondary or graduating valve for controlling said exhaust port and having a full release position and a retarded release position in which said exhaust port is restricted, and yielding resistance means for 70 returning said graduating valve to its full release position.

7. A triple valve device comprising a main valve having a brake cylinder exhaust port, a graduating valve controlling said 80 exhaust and having a normal release position and a further inward movement for restricting said exhaust, a movable abutment operated by an increase in train pipe pressure for moving said graduating valve 85 to its restricted position, and yielding resistance means for returning same to its full release position.

8. A triple valve device comprising a movable abutment and valve for controlling 90 the brake cylinder exhaust, means operating at the time of releasing the brakes for venting air from the auxiliary reservoir side of said abutment to move the valve to restrict the exhaust, and yielding resistance means 95 for returning the valve to full release position.

9. A triple valve device comprising a main valve having a brake cylinder exhaust port, a graduating valve controlling said 100 exhaust and having a normal release position and a further inward movement for restricting said exhaust, a movable abutment operated by an increase in train pipe pressure for moving said graduating valve 105 to its restricted position, a fixed stop for limiting the inward movement of the main slide valve, and a yielding resistance means for returning the graduating valve to its normal release position.

10. A triple valve device comprising a movable abutment and valve for controlling the brake cylinder exhaust and having a normal full release position and a further inward movement to a retarded release position in which the exhaust is restricted, means operating upon the movement of the valve to release position for reducing the pressure on the auxiliary reservoir side of said abutment and means for normally returning said valve to its full release position.

11. A triple valve device, comprising a valve and a movable abutment subject to the opposing pressures of the train pipe and 125 the auxiliary reservoir for operating said valve to control the brake cylinder exhaust, means operated by an increase in train pipe pressure when the brakes are applied, for venting air from the auxiliary reservoir side 130

of said abutment and moving said valve to restrict said exhaust, and means for normally opening said exhaust port.

12. A triple valve device comprising a main valve having a brake cylinder exhaust port and a vent port, a graduating valve for controlling said ports, a piston subject to train pipe pressure for operating said valves and having an inner retarded release position in which the exhaust port is restricted, and yielding resistance means for returning said piston and graduating valve to normal full release position.

13. In a fluid pressure brake, the combination with the train pipe, auxiliary reservoir, and brake cylinder, of a triple valve device having means operating under an increase in train pipe pressure for restricting the brake cylinder exhaust and closing communication from the auxiliary reservoir to the valve chamber, and means for normally opening said communication and said exhaust.

14. In a fluid pressure brake, the combination with the train pipe, auxiliary reservoir, and brake cylinder, of a triple valve device having a piston and valve operating upon an increase in train pipe pressure to close communication from the auxiliary reservoir to the valve chamber, to vent air from the valve chamber, and to restrict the brake cylinder exhaust, and yielding resistance means for normally opening the exhaust, and communication between the valve chamber and the auxiliary reservoir.

15. In a fluid pressure brake, the combination with the train pipe, auxiliary reservoir, and brake cylinder, of a triple valve device comprising a main valve having a brake cylinder exhaust port and a vent port for the valve chamber, and a graduating valve and piston having a movement relative to the main valve for controlling the said ports.

16. In a fluid pressure brake, the combination with the train pipe, auxiliary reservoir, and brake cylinder, of a triple valve device comprising a main valve having a brake cylinder exhaust port, a port for controlling communication between the valve chamber and the auxiliary reservoir, and a vent port for the valve chamber, and a graduating valve and piston having a movement relative to the main valve for controlling said ports.

17. A triple valve device, comprising a piston subject to variations in train pipe pressure, a valve operated by said piston for controlling the supply of fluid to and its release from the brake cylinder, and means for venting fluid from one side of said piston to cause the valve to move to release position.

18. In a triple valve, the combination of a main valve having a brake-releasing passage therethrough, a secondary valve con-

trolling said release passage, a piston operatively engaging both said valves whereby said release passage is open when said piston is in a position intermediate its two extreme positions, and means tending to move said piston and secondary valve from an extreme position to said intermediate position.

19. In a triple valve for air brakes, the combination of a main valve through which exhaust from the brake cylinder passes to release the brakes, a secondary valve controlling said exhaust, a valve-operating piston operatively connected to said main and secondary valves, said piston and secondary valve each having a full or unrestricted release position and a restricted release position, and a spring acting on said piston and tending to throw it to the full or unrestricted release position.

20. In a triple valve for air brakes, the combination of a main valve through which exhaust from the brake cylinder passes to release the brakes, a secondary valve controlling said exhaust, a valve-operating piston operatively connected to said main and secondary valves, said piston and secondary valve each having a full or unrestricted release position and a restricted release position, and means acting on said piston and tending to throw it to the full or unrestricted release position.

21. A triple valve device, comprising a piston, a main slide valve controlling a brake cylinder exhaust, an auxiliary valve operated by the piston to have a small movement relative to the main slide valve, and a yielding means for moving the auxiliary valve relative to the main slide valve to effect a free opening of the brake cylinder exhaust.

22. A triple valve device, comprising a main valve, an auxiliary valve having a small independent movement relative to the main valve, and a piston for actuating said valves, and having means operating under an increase of train pipe pressure at the forward part of the train to retard the release from the brake cylinder, and a spring for causing a movement of the auxiliary valve relative to the main valve to effect the free opening of the brake cylinder exhaust.

23. A triple valve device, comprising a main slide valve controlling a brake cylinder exhaust, a graduating valve having a small independent movement relative to the main valve, a piston for actuating said valves, and having means operating under an increase of train pipe pressure at the forward part of the train for restricting the brake cylinder exhaust, and a yielding resistance spring for moving the graduating valve relative to the main slide valve to effect a free opening of the brake cylinder exhaust.

24. A triple valve device comprising a main slide valve, an auxiliary valve and piston having a normal release position in which the brake cylinder exhaust is fully open, and a further inward movement relative to the main valve to a retarded release position in which the exhaust from the brake cylinder is restricted, and means for returning said auxiliary valve to its normal position.

25. A triple valve device, comprising a main slide valve, an auxiliary slide valve and piston having a slight movement relative to the main valve and a normal release position in which there is a free exhaust from the brake cylinder, and a further inward retarded release position, and a yielding resistance spring for returning the auxiliary valve and piston relative to the main valve from said inward position to normal release position.

26. In a fluid pressure brake system, the combination of a triple valve having a piston, a main valve with lost motion and a secondary valve operated by said piston, and a passage for releasing brakes controlled by both said valves, which may be restricted while the piston is moved to one limit of its traverse by increasing train pipe pressure and then opened when the secondary valve makes a partial movement in the opposite direction.

27. In a fluid pressure brake system, the combination of a triple valve having a piston, a main valve with lost motion and a secondary valve operated by said piston, a passage for releasing brakes so controlled by both valves that the passage may be restricted while the piston is actuated by admitting train pipe pressure and opened when the piston and secondary valve make a

partial movement in the opposite direction, and means for causing said partial movement.

28. In a fluid pressure brake system, the combination, with a triple valve having a piston capable of occupying three positions, one of which is intermediate the other two, a main and a secondary valve operated thereby, a passage controlled by both valves for releasing brakes, which is open while the piston occupies its intermediate position and a spring for moving the piston and secondary valve from one extreme to said intermediate position.

29. In a fluid pressure brake system, the combination, with a triple valve having a piston, a main valve, and a secondary valve operated thereby, of a passage through the main valve and controlled by the secondary valve for releasing brakes, which is opened while said piston occupies an intermediate position between two outer positions and means for moving said piston from one of its outer positions to said intermediate position.

30. In a triple valve, the combination of a main valve having a passage through it for releasing brakes, a secondary valve controlling said release passage, a piston for operating both said valves and for causing them to open said release passage while said piston is in the middle of three positions and means tending to move said piston and secondary valve from an outer position to said middle position.

In testimony whereof I have hereunto set my hand.

WALTER V. TURNER.
